United States Patent Office

Des. 211,675

Patented July 9, 1968

211,675

INVALID UNDERARM SUPPORT DEVICE FOR ATTACHMENT WITH WORKBENCHES AND THE LIKE

Charles E. Murcott, Valley Drive, Bay Crest,
Huntington, N.Y. 11743

Filed Apr. 3, 1967, Ser. No. 6,499

Term of patent 14 years

(Cl. D83—1)

The figure is a perspective view of an invalid underarm support device for attachment with workbenches and the like, showing my new design, the undisclosed opposite side is a mirror image of the side shown.

I claim:

The ornamental design for an invalid underarm support device for attachment with workbenches and the like, as shown.
